Patented Oct. 10, 1899.

H. McGINNIS.

DISPLAY CABINET FOR WINDOW SHADES.

(Application filed Dec. 31, 1898.)

(No Model.)

UNITED STATES PATENT OFFICE.

HENRY MCGINNIS, OF LA SALLE, ILLINOIS.

DISPLAY-CABINET FOR WINDOW-SHADES.

SPECIFICATION forming part of Letters Patent No. 634,472, dated October 10, 1899.

Application filed December 31, 1898. Serial No. 700,793. (No model.)

To all whom it may concern:

Be it known that I, HENRY MCGINNIS, of La Salle, in the county of La Salle and State of Illinois, have invented a new and Improved Display-Cabinet for Window-Shades, of which the following is a full, clear, and exact description.

My invention relates to improvements in devices designed for storing and displaying ready-mounted window-shades, whereby the shades may be kept entirely inclosed and readily displayed at any time, it being possible to display any shade desired and to readily find the same shade again.

15 My invention comprises the novel features hereinafter described and claimed.

Reference is to be had to the accompanying drawings, forming a part of this specification, in which similar characters of reference indicate corresponding parts in all the views.

20 Figure 1 is a perspective view of my device, showing a part of one side broken away. Fig. 2 is a cross-sectional elevation showing one side swung open, and Fig. 3 is a perspective view showing the adjustable bracket for carrying one end of the shade-roller.

25 In selling window-shades at retail the salesman has a great deal of trouble in properly exhibiting the shades and also by reason of the fact that the shades get mixed and a particular shade which has once been shown cannot be readily found again. The ordinary manner of displaying shades also results in great wear and tear on the shades, thus injuring considerable stock.

30 In my device the main stock is kept stored within compartments and is not touched, while a sample of each kind is mounted as if in place at a window and may be drawn down for display or run up for storage, as desired.

The storage part of my device consists of a series of compartments or pockets formed within the frame A and of such size as to conveniently hold the shades, and is provided 45 with a cover C and with side doors B. As herein shown, the cover is divided into two parts upon a central longitudinal line. Each half C of the cover is secured to the door B upon its side of the device, and the door and 50 cover are pivoted upon hinges b, located at one end of the door, so that the two may swing horizontally. The cover is preferably placed

at an incline, as shown in the drawings. The upper part of the cover forms a plate or shelf, to the under side of which are secured the 55 brackets by means of which the shade-rollers are supported. One end of the shade-roller may, if desired, be supported in fixtures secured to the bracket C', which is secured to the under side of the shelf or cover C. 60

One end of the cover C is provided with a series of longitudinally-extending slots D, and in these slots the fixture shown in Fig. 3 is placed. This fixture, as herein shown, is made of a plate of sheet metal consisting of 65 a body member or stem e, which at one end is provided with an eye e', adapted to receive the pin or journal at one end of the shade-roller. At its other end it is provided with transversely-extending members adapted to 70 engage the outer surface of a cover or shelf C and prevent the fixture from dropping. As herein shown, two such transverse members are shown, one member e² extending in one direction and the other member e⁴ extending 75 in the opposite direction. This fixture is also provided with a transverse member e³, extending from the body between the base formed by the transverse members e² and e⁴ and the pin-support e', and is so placed with reference 80 to the other transverse members or base that it will be close against the under surface of the shelf or cover C. It is also provided with a clamping bolt or screw e⁵, which may be set up against the under side of the cover, so as 85 to securely fix the device in place when adjusted. By means of the slots in the cover the fixture may be adjusted to accommodate shades of different widths. A series of these devices is secured to the under surface of the 90 cover, so that a number of shades may be put in place ready for exhibition. The number will depend upon the size of the cabinet.

In displaying the shades the door and the shelf will be swung open and the shades 95 pulled down in succession and exhibited, after which they are run up and the device is ready to be closed. The body of the stock will be kept in the pockets provided for it in the frame A and will not be taken out except 100 to fill an order.

The different styles may each be provided with a separate pocket, so that it is possible to tell at a glance how many shades of any

style are on hand, which will thus enable the salesman to avoid trouble caused by finding that there is not sufficient of any particular shade to fill an order after the purchaser has 5 left the store. The stock will also be kept clean and undamaged, even the shades which are used as samples being kept in condition, so that they may be used to fill an order.

The outer or swinging ends of the cover are 10 provided with suitable means for securing them in place and preventing them from swinging open. As herein shown, this means consists of a hook and staple H.

Having thus fully described my invention, 15 I claim as new and desire to secure by Letters Patent—

1. A displaying device for window-shades, comprising a supported shelf or plate member having a series of longitudinally-extending 20 slots in one end, roller-brackets fitting and sliding in said slots, and complementary roller-supports at the other end of the shelf, substantially as described.

2. A displaying device for window-shades, 25 comprising a supported shelf or plate member having a series of longitudinally-extending slots in one end, brackets fitting and sliding in said slots and adapted to support one end of the roller, means for locking the roller- 30 brackets in place when adjusted, and complementary roller-supports at the other end of the shelf, substantially as described.

3. A displaying device for window-shades, 35 comprising a rack adapted for the storage of stock, a cover pivoted at one end to swing horizontally, and shade-roller supports secured to said cover and adapted to receive sample rollers, substantially as described.

4. A display device for window-shades, comprising a rack adapted for the storage of stock, 40 a combined cover and door pivoted at one end to swing horizontally, and shade-roller supports secured to said cover and adapted to receive sample rollers, substantially as described.

5. A display device for window-shades, comprising a rack adapted for the storage of stock, 45 a combined cover and door pivoted at one end to swing horizontally, and shade-roller supports secured to said cover and adapted to receive sample rollers, the supports at one

end being adjustable toward and from those at the other end, substantially as described.

6. A display device for window-shades, comprising a rack adapted for the storage of stock, 55 a combined cover and door pivoted at one end to swing horizontally, shade-roller supports secured to said cover and adapted to receive sample rollers, the supports at one end being adjustable toward and from those 60 at the other end, and means for locking them in adjusted position, substantially as described.

7. A displaying device for window-shades, comprising a rack adapted for the storage of 65 stock, a cover pivoted at one end to swing horizontally, said cover having longitudinally-extending slots at one end, roller-brackets fitting and sliding in said slots, and complementary roller-bearings at the other end of 70 the cover, substantially as shown and described.

8. A displaying device for window-shades, comprising a rack adapted for the storage of 75 stock, a cover pivoted at one end to swing horizontally, said cover having longitudinally-extending slots at one end, roller-brackets fitting and sliding in said slots, means for locking them in adjusted position, and complementary roller-bearings at the other end 80 of the cover, substantially as described.

9. A bracket for shade-rollers, consisting of a plate having a longitudinal slit extending inward from each end and stopping short of each other, one of the divisions thus formed 85 at one end having means for holding an end of a shade-roller and the other being bent at right angles and the two divisions formed by the slit in the other end being bent at right angles to the body and oppositely. 90

10. A bracket for shade-rollers comprising a body having two lateral extensions facing each other and separated lengthwise of the body, one of the extensions having means for clamping an interposed part between the two, 95 said body having means for holding an end of a roller, substantially as described.

HENRY McGINNIS.
